(57) **CLAIM**

The ornamental design for a sock, as shown and described.

DESCRIPTION

FIG. 1 is a perspective view of a sock, showing my new design.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof.

FIG. 8 is a cross-sectional view of the sock of FIG. 4 along lines 8-8; and,

FIG. 9 is a perspective view of the sock of FIG. 1 when worn by a user.

The evenly dotted broken lines in the figures illustrating portions of the sock form no part of the claimed design. The evenly dotted broken lines illustrating a partial human figure and boot are directed to environment, and assist in illustrating how the sock may appear when worn in a position of use that form no part of the claimed design. The dash-dot-dash broken lines in the figures define boundary lines that form no part of the claimed design.
